RAILWAY RETARDER CLAMP

John A. Bodkin, New York, N. Y., and
Richard E. Bodkin, Westport, Conn.

Application August 31, 1953, Serial No. 377,619

9 Claims. (Cl. 188—62)

Our invention relates to railway car retarders of the known type which comprises an auxiliary or retarder rail positioned along a side of a railway track rail at a distance from this track rail smaller than the width of a wheel flange this retarder rail being movable against resilient pressure from this position farther away from the track rail whereby a wheel flange entering the space between these rails will receive lateral pressure and, hence, will be braked by friction.

One of us has shown and described a retarder of this type in his Patent No. 2,452,720. The present invention may be regarded as an improvement of the retarder shown in this patent and may use the same arrangement of rails, except for differences pointed out in the following description.

Objects of our invention are to compress track and retarder rail by very strong springs, thereby to retard a car very effectively, to provide counter-bearings for these springs which are connected by a member of a cross-section larger than the cross-section of a bolt which can pass through the rail webs, to incorporate this cross-section in a movable U-shaped member which has one leg passing through the rail webs and another leg passing under the rails whereby the cross-section of this latter leg, and hence the total cross-section of the member is not limited by the height of the webs, to connect the free ends of the mentioned legs by a bracket, and thereby to adapt this member for very strong stress.

Other objects are to secure a minimum distance between track rail and retarder rail, to adjust this minimum distance according to requirements, and to provide for this purpose abutments which are secured to the web-passing leg of the mentioned member between the rails in positions adjustable in the direction of this leg.

Further objects are to secure the correct mutual positions of the rails and clamping means permanently, to interpose a bracket between a spring and the track rail which bracket is supported or passed through by a web-passing leg and has a side shaped to fit the lateral cavity or recess of the track rail snugly, to support and to guide the retarder rail in its lateral movement by an underlying slide plate, thereby to make unnecessary guiding contact between the web-passing leg and the corresponding web bores whereby the frictional resistance against lateral movement of the retarder rail is diminished and a correct horizontal direction of this movement is secured, and to engage the foot of the track rail by this slide plate whereby a correct stationary position of the slide plate is secured.

Still other objects are to provide snubbers or shock absorbers which act parallel to the springs, thereby to secure a strong and shock-free spring and braking action, and to use the same brackets as spring and snubber bearings or housings.

Still further objects are to support the retarder rail slidably at a level higher than the level of the track rail, thereby to provide contact between the retarder rail and the braked wheel flange at a higher and larger surface,

2

and thereby to improve direction and intensity of the retarding pressure.

Still other objects and advantages will appear from the following description of exemplifying embodiments 5 of our invention, from the appended claims and from the accompanying drawing in which:

Fig. 1 shows a top view of an illustrative embodiment of our invention, the rails being broken off.

Fig. 2 shows a partially sectional vertical view of the 10 same embodiment, the sectionally represented parts being cut along the line 2—2 in Fig. 1.

Fig. 3 shows a side view of the same embodiment, seen from the left side of Fig. 2.

Fig. 4 shows a top view of a simplified embodiment, 15 rails being broken off.

Fig. 5 shows a partly sectional vertical view of the latter embodiment, the sectionally represented parts being cut along the line 5—5 in Fig. 4.

Referring to Figs. 1 to 3, numeral 1 indicates one of 20 the two rails of a railway track which is stationarily secured on ties (not shown) in usual manner. Two slide plates 3 may be secured in similar manner, for example by spikes passing through holes 4 provided near the ends of the plates 3. Preferably, each plate 3 has a portion 25 underlying and contacting the rail 1 and engaging the same by means of lip-like projections 6 and 7. Another portion 8 of each plate 3 extends horizontally at a right angle to the rail 1 to one side, preferably to the side which is the inner side of the railway track. The upper side of 30 the plate 3 forms an upward step from the first mentioned portion to the portion 8 whereby the latter is higher than the first portion or than the base of the rail 1. The upper side of the plate portion 8 forms a smooth surface extending horizontally aside of the rail 1.

An auxiliary or retarder rail 9 is slidably positioned on the plate portion 8 and extends along the rail 1 at a variable distance. The rail 9 has preferably the same standard cross-section as the rail 1, except that a portion 35 of the foot of the rail 9 may be cut off in order to allow 40 positioning of the rail 9 close to the rail 1. The rail 9 is urged toward the rail 1 by a clamp which is constructed as follows:

A U-shaped member 11 has a yoke or bent end so arranged that the rail 9 is positioned in the horizontal distance between this bent end and the rail 1, and has two 45 legs extending from this yoke horizontally, one over the other. The upper leg 12 is provided with a shoulder 13 forming a surface facing toward the free end of the leg 12. A leg portion 14 of reduced diameter extends from the shoulder 13 to the free leg and is threaded. This leg portion passes, in the direction from the shoulder, first through the web of the rail 9, then through the web of the rail 1. The lower leg 15 passes under the rails 9 and 1 has a threaded end.

A bracket 16 is secured to and connects the free ends of the legs 12 and 15. Preferably, the bracket 16 has bores for the passage of the legs and is secured to the same near their free ends by nuts 17 and 18 threaded on the legs. The bracket side opposite to the nut 17 forms a 55 surface facing the shoulder surface 13. The member 11 and the bracket 16 form a movable unit capable of withstanding high stress.

Resilient pressing means or springs are positioned between the shoulder 13 and the rail 9 or between the 60 bracket 16 and the rail 1, or preferably at both these places. For example, a leaf spring 19 composed of several layers bears against the shoulder 13 and has a bore for the passage of the leg portion 14, and a coiled spring 20 bears against the bracket 16 and surrounds the leg portion 14. The springs 19 and 20 may bear on the respective rails directly or through interposed members. For example, a bracket 21 is positioned between the spring

20. and the rail 1, has a bore for the passage of the leg portion 14 and is shaped to fit the cavity or recess between head and foot of this rail snugly.

In addition to and aside of the spring 20, one or more snubbers 22 are positioned between the brackets 16 and 21. Preferably two snubbers of any known and suitable structure are positioned substantially at the same level as the spring 20 and extending parallel and symmetrically to the spring 20. The brackets are shaped to secure the position of the snubbers. For example, the facing surfaces of the brackets may have cylindrical projections 23 fitting corresponding recesses in the ends of the snubbers. In addition, the bracket 21 has lateral walls 24, and the bracket 16 has lateral walls 25 and a top wall 26 whereby the bracket 16 forms an open housing into which the snubbers 22 and the spring 20 enter.

The described springs urge the rail 9 toward the rail 1 whereby they tend to reduce the distance between the rails to a minimum. This minimum distance is determined by abutments spacing the rails. Preferably, these abutments are formed by two nuts 27 which are threaded on the leg portion 14 between the rails. The minimum distance can be adjusted by screwing rotation of either nut 27. In addition, the nuts 27 and 17 allow adjustment of the tension of the springs.

In Fig. 2, the lower part of the outline of a car wheel is indicated by the dotted line 28. The minimum distance between the rails 1 and 9 is so adjusted that the space between the heads of the rails is narrower than the wheel flange. Hence, when a wheel enters this space, it forces the rail 9 away from the rail 1 against the braking pressure of the springs.

One or more retarder units of the type described may be provided for one railway track. For example, identical units may be positioned symmetrically at both rails of the track, and identical units using the same retarder rail may be positioned along this common retarder rail.

The embodiment shown in Figs. 4 and 5 is designed for less heavy duty or lesser braking force and constitutes a simplification of the embodiment shown in Figs. 1 to 3. The simplified embodiment does not comprise snubbers. It has a U-shaped member 31 similar to the member 11, but shorter, a bracket 36 secured near the free end of the legs of the member 31, and a leaf spring 39 replacing the coiled spring 20 and bearing against the bracket 36 and, on the other side, directly against the rail 1. The retarder rail 29 is identical to the rail 9 in Figures 1 to 3, except that more of the foot of the rail 29 is cut away. The spring 19 and the nuts 17, 18 and 27 are identical to the parts indicated by the same numerals in the first described embodiment.

Any of the mentioned nuts may be provided with a washer of any known and suitable type. For example, Figs. 4 and 5 show a washer 32 provided for the nut 17. The simplified embodiment may be used without a slide plate or may be provided with a slide plate similar to the plate 3 shown in Figs. 1 to 3.

The function of the two described embodiments is substantially the same.

We desire it understood that our invention is not confined to the particular embodiments shown and described, the same being merely illustrative, and that our invention may be carried out in other ways within the scope of the appended claims without departing from the spirit of our invention as it is obvious that the particular embodiments shown and described are only a few of the many that may be employed to attain the objects of our invention.

Having described the nature of our invention, what we claim and desire to protect by Letters Patent is:

1. A clamp for connecting a track rail and a retarder rail extending along and aside of said track rail at a variable distance therefrom, said clamp comprising a rigid U-shaped member having a yoke end and having two elongated legs extending, one over the other, horizontally from said yoke end, said legs having ends far from said

yoke end, the upper leg having a shoulder positioned near said yoke end and forming a surface facing toward said far end of this leg, said upper leg having a portion extending from said shoulder to said far end, said clamp further comprising a bracket secured to and connecting said far leg ends and having a surface facing said shoulder surface, and a spring positioned on said upper leg portion between said surfaces.

2. A clamp for connecting a track rail and a retarder rail extending along and aside of said track rail at a variable distance therefrom, said clamp comprising a rigid U-shaped member having a yoke end and having two elongated legs extending, one over the other, horizontally from said yoke end, said legs having ends far from said yoke end, the upper leg having a shoulder positioned near said yoke end and forming a surface facing toward said far end of this leg, said upper leg having a portion extending from said shoulder to said far end, the lower leg having a considerable vertical distance from said upper leg, said clamp further comprising a bracket secured to and connecting said far leg ends and having a surface facing said shoulder surface, and a spring positioned on said upper leg portion between said surfaces.

3. A clamp for connecting a track rail and a retarder rail extending along and aside of said track rail at a variable distance therefrom, said clamp comprising a rigid U-shaped member having a yoke end and having two elongated legs extending, one over the other, horizontally from said yoke end, said legs having ends far from said yoke end, the upper leg having a shoulder positioned near said yoke end and forming a surface facing toward said far end of this leg, said upper leg having a portion extending from said shoulder to said far end, said clamp further comprising a bracket secured to and connecting said far leg ends and having a surface facing said shoulder surface, and two springs, positioned on said upper leg portion.

4. A clamp for connecting a track rail and a retarder rail extending along and aside of said track rail at a variable distance therefrom, said clamp comprising a rigid U-shaped member having a yoke end and having two elongated legs extending, one over the other, horizontally from said yoke end, said legs having ends far from said yoke end, the upper leg having a shoulder positioned near said yoke end and forming a surface facing toward said far end of this leg, said upper leg having a portion extending from said shoulder to said far end, said clamp further comprising a bracket secured to and connecting said far leg ends and having a surface facing said shoulder surface, two abutments secured to said leg portion between said surfaces, and a spring positioned on said upper leg portion between said surfaces.

5. A clamp for connecting a track rail and a retarder rail extending along and aside of said track rail at a variable distance therefrom, said clamp comprising a rigid U-shaped member having a yoke end and having two elongated legs extending, one over the other, horizontally from said yoke end, said legs having ends far from said yoke end, the upper leg having a shoulder positioned near said yoke end and forming a surface facing toward said far end of this leg, said upper leg having a portion extending from said shoulder to said far end, said clamp further comprising a bracket secured to and connecting said far leg ends, another bracket positioned between said first bracket and said shoulder, and a spring positioned between said brackets.

6. A clamp for connecting a track rail and a retarder rail extending along and aside of said track rail at a variable distance therefrom, said clamp comprising a rigid U-shaped member having a yoke end and having two elongated legs extending, one over the other, horizontally from said yoke end, said legs having ends far from said yoke end, the upper leg having a shoulder positioned near said yoke end and forming a surface facing toward said far end of this leg, said upper leg having a portion extending from said shoulder to said far end, said clamp

further comprising a bracket secured to and connecting said far leg ends, another bracket positioned between said first bracket and said shoulder, a spring positioned on said upper leg portion between said brackets, and a snubber positioned between said brackets aside of said spring.

7. A retarder for railway cars, comprising a track rail; a plate having a horizontal upper surface extending aside of said track rail; a retarder rail slideable on said upper plate surface; and a clamp comprising a rigid U-shaped member having a yoke end and having two legs extending, one over the other, horizontally from said yoke end, said legs having ends far from said yoke end, the upper leg having a shoulder positioned near said yoke end and forming a surface facing toward said far end of this leg, said upper leg having a portion extending from said shoulder first through the web of said retarder rail and then through the web of said track rail to said far end of this leg, the lower leg passing under said rails, a bracket secured to and connecting said far leg ends and having a surface facing said rails and said shoulder, and a spring bearing against one of said surfaces and against that rail which is nearest to said latter surface.

8. A retarder for railway cars, comprising a track rail; a plate having a portion underlying and engaging said track rail and another portion having a horizontal upper surface extending aside of said track rail; a retarder rail slideable on said upper plate surface; and a clamp comprising a rigid U-shaped member having a yoke end and having two legs extending, one over the other, horizontally from said yoke end, said legs having ends far from said yoke end, the upper leg having a shoulder positioned near said yoke end and forming a surface facing toward said far end of this leg, said upper leg having a portion

extending from said shoulder first through the web of said retarder rail and then through the web of said track rail to said far end of this leg, the lower leg passing under said rails, a bracket secured to and connecting said far leg ends and having a surface facing said rails and said shoulder, and a spring bearing against one of said surfaces and against that rail which is nearest to said latter surface.

9. A retarder for railway cars, comprising a track rail; a plate having a portion underlying said track rail and another portion higher than said first plate portion and having a horizontal upper surface extending aside of said track rail; a retarder rail slideable on said upper plate surface; and a clamp comprising a rigid U-shaped member having a yoke end and having two legs extending, one over the other, horizontally from said yoke end, said legs having ends far from said yoke end, the upper leg having a shoulder positioned near said yoke end and forming a surface facing toward said far end of this leg, said upper leg having a portion extending from said shoulder first through the web of said retarder rail and then through the web of said track rail to said far end of this leg, the lower leg passing under said rails, a bracket secured to and connecting said far leg ends and having a surface facing said rails and said shoulder, and a spring bearing against one of said surfaces and against that rail which is nearest to said latter surface.
